ANTIFRICTION GUIDEWAY FOR SLIDABLE
VISE JAWSMichael F. Ward, Chicago, Ill., assignor to Student-
baker Machine Co., Maywood, Ill., a corpora-
tion of Illinois

Application October 8, 1945, Serial No. 620,939

2 Claims. (Cl. 81—17.2)

1

The present invention relates to a vise construction and more particularly to the construction of a hydraulic vise having means to practically eliminate all friction between the fixed and movable jaw members.

While the present invention will herein be illustrated and described as a hydraulic vise, it is to be understood that the improvements may be incorporated in vises, or similar machines, other than hydraulic vises.

In the operation of some vises, and particularly hydraulic vises, a considerable amount of force is necessary to hold the movable jaw member against the work piece which is against the fixed jaw. Where such a vise is hydraulically operated, a heavy load is imposed upon the movable jaw member, and sometimes quite an effort is needed to separate the movable jaw member from the work piece when the job is finished.

It is, therefore, an important object of the present invention to provide a vise construction in which the movable jaw member is mounted on the fixed jaw member, with anti-friction means, to enable easy operation of the movable jaw member towards and away from the fixed jaw.

Another object of the present invention is to provide a hydraulic vise having a ball bearing support for the movable jaw member.

Another object of the present invention is to provide a hydraulic vise having a minimum of friction between the movable jaw member and the fixed jaw member.

A still further object of the present invention is to provide a hydraulic vise having cooperating ways for ball bearings and gibs for retaining the balls within the length of the movable jaw member.

Another and yet further object of the present invention is to provide a vise construction in which the movable jaw member is supported on the fixed jaw member by ball bearings, which bearings support the entire weight of the movable jaw member.

The invention has for a further object the provision of a practically frictionless vise construction.

The above, other and further objects of the present invention will be apparent from the following description and accompanying drawings.

An embodiment of the present invention is illustrated in the accompanying drawing and the views thereof are as follows:

Figure 1 is a side elevational view of a hydraulic jack embodying the present invention.

Figure 2 is a vertical sectional view taken in the plane of line II—II of Figure 1.

Figure 3 is a view, partially in end elevation and partially in section, taken in the plane of line III—III of Figure 1.

Figure 4 is a top plan view of the vise of Figure 1.

The drawing will now be explained.

Referring to Figure 1, a vise is illustrated including a fixed jaw member A and a movable jaw member B. The fixed jaw member A has an elongated body having feet 5 and 6 for resting on a surface, such as a bench, and an upwardly and inwardly turned end 7 providing a fixed jaw 8. The face of the jaw 8 has a hardened plate insert 9, retained by suitable screws.

The foot 5 has an end extension 11 slotted at 12 to receive a lag screw or bolt for securing this end of the vise to a support. The feet 6, which extend laterally of the fixed member A, as shown in Figure 4, are provided with similar slots 13 for a similar purpose.

Set into the upper portion of the fixed member A is a plate 14 horizontally disposed and fastened in place by suitable bolts 15. The plate 14 is horizontally disposed with a horizontal upper surface 16. Side margins 17 and 18, of the plate 14 are vertical and each has formed in it a lengthwise extending semi-cylindrical groove 19 and 20, respectively. The grooves being formed with their diameters in the vertical faces or margins of the side surfaces of the plate 14.

The movable jaw member B has an end portion 21 constituting a movable jaw, which portion is provided with a hardened plate 22 held in place by suitable screws.

As may be observed in Figure 2, the movable jaw member B straddles the plate 14 of the fixed jaw member.

Attached to opposite sides of the movable jaw member B are plates 23 and 24 held in place by suitable screws or bolts 25. The plates 23 and 24 lap the side margins of the plate 14 of the fixed member A. The inner faces of the plates 23 and 24 are formed with lengthwise extending grooves 26 and 27, respectively, the grooves 26 and 27 in the side plates complementing the grooves 17 and 18 in the side margins in the plate 14 to provide ball bearing ways, or race-ways, for receiving ball bearings 28. It will be observed, in Figure 2, that the entire weight of the movable jaw member B is carried by the ball bearings 28 to reduce friction to a minimum.

The balls 28 are retained in the ways within the length of the movable jaw member B by means of gibs 29 and 30 applied to the ends of the side plates 23 and 24 of the movable jaw member, which plates are recessed at 31 to strad-

idle the plate 14 of the member A, as may be observed in Figure 3. The gibbs are held in place by screws 32 which engage threaded apertures in the ends of the movable jaw B.

A spring 33 is hooked at one end to a suitable projection 34 in the left-hand end of the fixed member A. The other end of the spring is hooked over a projection 35 in the movable jaw member, adjacent the jaw 21 of the same, to normally withdraw the movable jaw member B from the jaw 8 of the fixed member A.

A ram 36 entered in the movable jaw member B is positioned therein to move the jaw member to the right, as viewed in Figures 1 and 4, whenever hydraulic pressure is applied to it.

Hydraulic pressure is applied to the ram 36 by connection of a suitable source of pressure to the adapter or coupling, indicated generally at 37.

It is to be understood that the movable jaw member is moved toward the fixed jaw member by hydraulic pressure applied to the ram 36, which pressure is regulated by a suitable valve, usually actuated by a treadle engageable by a foot of the vise operator. The movable jaw member is moved against a work piece to clamp it between the fixed jaw and movable jaw, by hydraulic pressure, and held as long as is necessary for the operator to do anything on the work piece.

When work has been finished, pressure against the ram 36 is relieved, whereupon the spring 33 functions to withdraw the movable jaw from the fixed jaw and release the work piece theretofore held between the same.

It will be evident that the ball bearing mounting of the movable member B on the fixed member A, in the manner illustrated and described, reduces friction to a minimum and all of the weight of the movable jaw member is carried on and supported by the balls 28 of the ball bearings.

The ball bearing grooves 17, 18, 26 and 27, 40 heretofore described, were described as each being semi-cylindrical. In actual practice these grooves, when brought together to form ball receiving ways, are slightly less than truly semi-cylindrical, to enable the confronting faces of the plates 23 and 24 in the side margins of the plate 14 to be separated a slight distance, to prevent any binding between the movable jaw member and the fixed jaw member.

It will be observed that the vise construction herein disclosed is one which will enable the manufacture of a practically frictionless vise, at minimum cost, as the parts are simple, and of such nature as to be readily formed and machined, as well as assembled, in an expeditious manner.

A second spring 33a is shown as parallel to spring 33. The spring 33a is hooked at one end to a projection 34a on the left-hand of member A. The other end of the spring is hooked over a projection 35a in the movable jaw member, adjacent the jaw 21 of the same, to cooperate with

spring 33 to withdraw the movable jaw member B from the fixed jaw 8.

A screw 38 is threaded into the end piece 39 of member A to serve as a stop for retrograde movement of the movable jaw member B under influence of springs 33 and 33a.

The invention has herein been described more or less precisely as to details, yet it is to be understood that the invention is not to be limited thereby, as changes may be made in the arrangement and proportion of parts, and equivalents may be substituted, without departing from the function and scope of the invention.

The invention is claimed as follows:

1. A hydraulic vise comprising an elongated base member supporting a fixed jaw, a plate fastened flatwise to said base and having vertical side margins, a movable jaw member, said movable jaw member having side plates lapping the vertical side edges of said first plate, the vertical side edges of said first plate and the confronting faces of said plates having complementary grooves formed in them constituting ball bearing ways adjacent the opposite marginal portions of the vise, ball bearings in said ways, and means confining the balls within the lengths of the said side plates, the construction being such that the entire weight of the movable jaw member is supported solely by said balls.

2. A hydraulic vise comprising an elongated base member supporting a fixed jaw, a horizontally disposed plate fastened to said base and having side margins, each of said side margins having a lengthwise extending semi-cylindrical groove formed in it with the diameter of the groove vertical, a movable jaw member, side plates secured to said movable jaw member, each of said side plates having a lengthwise semi-cylindrical groove in its inner face to complement the adjacent groove in said base plate to form ball raceways, ball bearings in said raceways confined within the length of said side plates, and gibbs confining said balls to said movable jaw member.
